UNITED STATES PATENT OFFICE.

MINAL E. YOUNG, OF CASPER, WYOMING.

DIAMOND-DRILL BIT.

Application filed September 4, 1924. Serial No. 735,948.

To all whom it may concern:

Be it known that I, MINAL E. YOUNG, a citizen of the United States, residing at Casper, in the county of Natrona and State of Wyoming, have invented certain new and useful Improvements in Diamond-Drill Bits, of which the following is a specification, reference being had to the accompanying drawings.

10 This invention relates to certain improvements in diamond drill bits and has relation more particularly to a bit of this kind comprising a cylindrical member having cutting diamonds set in its working end portion and projecting beyond the inner and outer surfaces thereof, and it is an object of the invention to provide novel and improved means whereby diamonds projecting beyond the outer surface of the member are 15 effectively protected against excessive wear, abrasion, breakage or being torn out of their seatings when lowering the bit through hard rock or a casing.

Another object of the invention is to provide a diamond drill bit with outstanding flanges positioned in close proximity to the diamonds and which operate to keep the diamonds from striking the hard surface of a casing or hard rock which would cause 20 breakage of the diamonds during the process of lowering or extracting the bit.

The invention consists in the details of construction and in the combination and arrangement of the several parts of my improved diamond drill bit whereby certain important advantages are attained and the device rendered simpler, less expensive and otherwise more convenient and advantageous for use, as will be hereinafter more 25 fully set forth.

The novel features of my invention will hereinafter be definitely claimed.

In order that my invention may be the better understood, I will now proceed to 30 describe the same with reference to the accompanying drawings, wherein:

Figure 1 is a longitudinal sectional view taken through a bit constructed in accordance with an embodiment of my invention;

35 Figure 2 is a view in plan of the bottom or working end of the bit as herein disclosed.

As disclosed in the accompanying drawings, B denotes a hollow cylindrical bit having one end portion provided with the external threads 1 whereby the bit may be

properly engaged with the rods and lowered into a drill hole. The bit B has seated in its lower or working end portion in a well-known manner the diamonds 2, said diamonds 2 projecting beyond the outer and 60 inner surfaces of the bit B.

When a bit of this type is lowered into a drill hole the diamonds 2 projecting beyond the outer surface or circumference of the bit are subject to excessive wear, abrasion, 65 breakage, and are sometimes torn out of their seatings in the bit through rubbing or striking against the inside of the drill hole. When the drill hole has been lined with iron pipe or casing, the bit B has to be lowered 70 with the outer diamonds 2 in actual contact with the more or less roughened inner surface of this pipe or casing. If the casing is broken, bent, roughened, or collapsed, it is often impossible to use a diamond bit 75 without a costly loss of diamonds. This condition is accentuated in the deeper drill holes, as in oil well drilling, where several thousand feet of casing are often employed and the bit B has to be lowered and raised 80 through this length of casing.

To avoid these manifest objections and to protect these outer diamonds 2, I provide on the outer surface or periphery of the bit B directly above said outer diamonds 2 or the 85 settings therefor the outstanding flanges 3 disposed lengthwise of the bit with the outer ends thereof in relatively close proximity to the outer or working end of the bit. These flanges 3 extend outwardly from the periphery or circumference of the bit an appreciable distance beyond the cutting edges of the outer diamonds 2. This provision of the flanges 3 gives absolute protection to these outer diamonds 2 against the objections and 90 disadvantages hereinbefore referred to. This is due to the fact that all the wear or striking against the wall of the drill hole or the pipe or casing is upon the inexpensive flanges 3 rather than upon the expensive diamonds 2. 95

These flanges 3 may be of any size, shape or cross section that will adequately protect such outer diamonds 2 and said flanges may be integral with the bit or the flanges may be 100 made separate and affixed to the bit in any manner desired. These flanges may also be made of a metal tempered harder or softer than the bit itself as the use in a particular hole may require. 110

In lowering, these flanges 3 may be slightly worn down and subsequent rotation at the bottom of the hole will further wear them down, the amount of this wear, however, being dependent on the hardness to which the flanges are tempered. These flanges should be tempered just hard enough and project just far enough beyond the outer diamonds 2 so that sufficient portions of the flanges 3 10 will remain to protect the diamonds when the bit is being raised out of the hole.

From the foregoing description it is thought to be obvious that a diamond drill bit constructed in accordance with my invention is particularly well adapted for use by reason of the convenience and facility with which it may be assembled and operated, and it will also be obvious that my invention is susceptible of some change and modification 20 without departing from the principles and spirit thereof and for this reason I do not wish to be understood as limiting myself to the precise arrangement and formation of the several parts herein shown in carrying 25 out my invention in practice except as hereinafter claimed.

I claim:—

1. The combination with a drill bit having diamonds projecting beyond its periphery at the working end thereof, of protecting 30 flanges of soft metal carried by the bit and projecting outwardly beyond the diamonds, said flanges being arranged above the diamonds.

2. The combination with a drill bit having 35 diamonds projecting beyond its periphery at the working end thereof, of protecting flanges of soft metal carried by the bit and projecting outwardly beyond the diamonds, said flanges being arranged above the dia- 40 mons and terminating in relatively close proximity thereto.

3. A combination with a drill bit having diamonds at the working end thereof, of protecting flanges of soft metal carried by 45 the bit and projecting outwardly beyond the diamonds, said flanges being arranged above the diamonds and terminating in relatively close proximity thereto.

In testimony whereof I hereunto affix my 50 signature.

MINAL E. YOUNG.
